LEE S. CHADWICK, OF CLEVELAND, OHIO, ASSIGNOR TO THE CLEVELAND FOUNDRY COMPANY, OF CLEVELAND, OHIO, A CORPORATION OF OHIO.

BURNER.

1,138,729.

Specification of Letters Patent.

Patented May 11, 1915.

Application filed October 25, 1913. Serial No. 797,916.

To all whom it may concern:

Be it known that I, LEE S. CHADWICK, a citizen of the United States, residing at Cleveland, in the county of Cuyahoga and State of Ohio, have invented a certain new and useful Improvement in Burners, of which the following is a full, clear, and exact description, reference being had to the accompanying drawings.

10 This invention relates to burners for stoves and more particularly to wick burners in the operation whereof the wick is, or may be, turned into engagement with an abutment (as part of the flame spreader) 15 whereby its height is limited. In the operation of burners of this kind and especially in the operation of the type shown in patent to Jeavons No. 848,828, wherein a drum surrounds the top of the wick tubes and extends thereabove, it is customary to turn the wick up to its most elevated position and to 20 ignite the outer surface of the wick through the door of the drum. No special harm will follow from this operation unless the door 25 of the drum is left open. In such case, the proper balance of drafts within the burner and within the drum is disturbed, the flame licks around and greatly heats the spreader, increasing the vaporization at the inner 30 surface of the wick, and the vapor there produced falls by gravity downwardly within the inner wick tube and becomes ignited. Owing to the heating of the parts, the amount of vapor thus evolved becomes so 35 great that a flame of considerable volume may be produced, sufficient to unsolder the connections between the burner and the supply pipe and to allow the oil to escape freely and be ignited by this flame.

40 It is the object of this invention to provide means whereby, in the event of such flame being produced within the inner wick tube, an upward draft therefor may be automatically provided, whereby the parts liable 45 to permit the escape of oil will be protected against the action of the flame and the danger of fire will be eliminated.

Still further and more generally speaking, the invention may be defined further as 50 consisting of the combinations of elements embodied in the claims hereto annexed and illustrated in the drawings forming part hereof, wherein—

55 Figure 1 represents a vertical sectional view through a burner and drum having my

invention applied thereto; Fig. 2 a sectional view corresponding to the line 2—2 of Fig. 1, looking upwardly; Fig. 3 a view similar to Fig. 1 showing the positions of the parts of the burner after the operation of my invention; and Fig. 4 is a sectional detail illustrating a modification of the invention shown in the preceding figures. 60

Describing by reference characters the various parts illustrated herein, 1 represents the inner and 2 the outer wick tube of the burner. 3 denotes the wick within said tubes, said wick being provided with a carrier 4 which is adapted to be engaged by the usual star wheel on the wick-raiser 65 shaft 5.

6 Denotes a laterally projecting coupling which is soldered to the lower outer surface of the outer wick tube and which is provided with a channel 7 whereby communication is 70 established between the burner supply pipe (not shown) and the space between the wick tubes. The connection 6 may be secured in operative relation to the supply pipe in any desired manner, as for instance in the manner shown in the patent to Jeavons No. 1,039,950, issued October 1, 1912. 75

8 Denotes the outer and 9 the inner ring of a centering device for the spreader, said rings being connected by the inclined arms 80 10. The inner ring forms a guide for the spindle 11, which is connected to the flame spreader. This spreader is of the type shown in the Jeavons Patent No. 951,612, issued March 8, 1910 and, when in place, the 85 lower plate 12 thereof is in engagement with the top of a cylindrical ring 13 which extends upwardly from the perforated frusto conical ring 14, the lower cylindrical end flange 15 whereof is secured to the upwardly 90 projecting ring 16 which, together with the attached cylindrical end flange 15 is supported upon the outer ring 8 of the centering device. The ring 16 extends somewhat above the tops of the wick tubes, and its 95 upper end is deflected inwardly, as shown at 17. The rings 14 and 16 will be provided with perforations, and, if found desirable some of the perforations of the ring 16 may be located in the projection 17 thereof. The 100 parts 13, 14 and 15 constitute an internal air distributor.

18 Denotes a perforated plate which extends transversely across the bottom of the frusto conical portion 14 of the air dis- 110

tributer. This plate is rigid with the other parts of the distributor and carries at its lower end a locking device 19 which is adapted to engage the arms 10 in the manner shown, described, and claimed in Jeavons Patent No. 871,593, issued November 15, 1907.

It will be noted that the spindle 11 passes through the central portion of the plate 18 and through the ring 9, the spreader 11^a carried thereby being centered by said ring and plate. When in operative position, the lower spreader plate 12 is in contact with the top of the cylindrical extension 13 of the air distributer. A spiral spring 20 surrounds the spindle 11 and bears at one end against the top of the plate 18, which constitutes an abutment for this end of the spring, and at its other end against the spreader, which constitutes an abutment for such other end of the spring, whereby the spring tends to elevate the spreader and the spindle and to separate the bottom of the spreader from the top of the distributer. To retain the spreader in operative relation to the wick tubes and the air distributer, a washer 21 is applied to the spindle beneath the plate 18 and is soldered to said spindle, the soldering surface being extended by the neck 21^a. A solder fusible at a comparatively low temperature will be employed.

From the foregoing description, it is believed that the operation will be readily understood. Assuming that the operator leaves the door 22 of the drum 21 open, with the wick 3 in substantial engagement with the lower spreader plate, and that the flame unduly heats the spreader and that the vapors evolved from the inner side of the wick are ignited within the inner wick tube. Before any injurious results can be produced, the solder by which the washer 21 is attached to the spindle 11 will have been melted, and thereupon the spring 20 will elevate the spreader and the spindle, frequently, with sufficient force to cause them to assume the position shown in Fig. 3. A free and unobstructed draft for the vapors within the interior of the inner wick tube is then provided, and the wick will operate in substantially the same manner as an ordinary burner of the wick type and without any serious danger to the operator, the burner parts, or the apartment within which the stove or burner may be located.

In Fig. 4 there is shown a modification of the means for holding the spreader and the spindle in operative relation to the wick tubes and air distributer. In this figure, a washer 22 is applied to the spindle 23, above a fusible pin 24, which extends through a suitable hole in the spindle. The operation, however, is substantially identical with that of the preceding modification, the heat produced by the flame in the inner wick tube

being sufficient to melt the fusible pin 24 and to permit the spreader to elevate the spindle.

Having thus described my invention, what I claim is:—

1. In a burner, the combination of inner and outer wick tubes, a spreader extending above the upper ends of said tubes and spaced therefrom, a wick within the space between the wick tubes, and means operative by temperature changes for automatically moving the spreader away from the top of the wick tubes. 70

2. In an oil burner, the combination of inner and outer wick tubes and a wick therebetween, an abutment for the top of the wick, and means, operative by temperature changes, for automatically moving said abutment away from the top of the wick tubes. 80

3. In an oil burner, the combination of inner and outer wick tubes and a wick therebetween, an abutment for the top of the wick, and means, operative by temperature changes, for automatically separating the abutment and the wick. 90

4. In an oil burner, the combination of inner and outer wick tubes and a wick therebetween, an abutment for the top of the wick, and means, operative by temperature changes, for varying the distances between the wick tubes and the abutment. 95

5. In an oil burner, the combination of inner and outer wick tubes and a wick therebetween, a flame spreader having a surface against which the top of the wick is adapted to abut, a spindle carried by said spreader and projecting within the inner wick tube, a spring surrounding said spindle and tending to elevate the spreader, and fusible means normally retaining the spreader in a predetermined position with reference to the tops of the wick tubes, against the action of said spring. 100

6. In an oil burner, the combination of inner and outer wick tubes and a wick therebetween, a flame spreader having a surface against which the top of the wick is adapted to abut, a spindle projecting downwardly within the wick tubes from the spreader, a centering device for said spindle within the inner wick tube, a spring surrounding the spindle and bearing against said centering device and tending to elevate the spreader, and an abutment carried by the spindle and having a fusible connection therewith, the abutment being on the opposite side of the centering device from the spring. 115

7. In an oil burner, the combination of inner and outer wick tubes and a wick therebetween, a spreader having a surface extending above the wick tubes and adapted to be engaged by the wick, a spindle carried by said spreader and projecting within the inner wick tube, an abutment through which said spindle extends, a spring on one side of 120

- said abutment and surrounding the spindle and tending to elevate the spreader, and a device on the opposite side of said abutment from the spring and fusibly connected to the spindle and normally retaining the spreader in a predetermined position with reference to the top of the wick tubes, against the action of the spring.
8. In an oil burner, the combination of inner and outer wick tubes and a wick therebetween, an abutment extending above the tops of the wick tubes and adapted to be engaged by the top of the wick, means tending to move said abutment away from the top of the wick tubes, and a fusible device operatively connected with said abutment and normally preventing its movement away from said wick tubes.
9. In a burner, the combination of inner and outer wick tubes and a wick therebetween, and means, operative by temperature changes, for automatically varying the draft through the inner tube.
10. In a burner, the combination of inner and outer wick tubes and a wick therebetween, and means, operative by temperature changes, for automatically increasing the volume of air flowing through the inner tube.
11. In a burner, the combination of inner and outer wick tubes and a wick therebetween, and means including a fusible element for automatically varying the draft through the inner tube.
12. In an oil burner, the combination of inner and outer wick tubes and a wick therebetween, and means for varying the draft through the inner tube, said means including a draft controlling member, a spring arranged to operate said member, and a fusible device normally preventing such movement of the member by said spring.
13. In a burner, the combination of inner and outer wick tubes, a wick therebetween, and means, operative by temperature changes, for automatically varying the effective area of the opening through which the draft in the inner tube flows.
14. In a burner, the combination of inner and outer wick tubes and a wick therebetween, and means including a fusible element for automatically varying the effective area of the opening in the inner wick tube through which the draft flows.
15. In an oil burner, the combination of inner and outer wick tubes and a wick therebetween, and means for varying the effective area of the opening within the inner wick tube through which the draft flows, said means including a draft controlling member, a spring arranged to operate said member, and a fusible device normally preventing such movement of the member by said spring.
- In testimony whereof, I hereunto affix my signature in the presence of two witnesses.
